UNITED STATES PATENT OFFICE.

EDWARD ERICKSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON SHOE BOTTOMS.

Application filed June 3, 1920. Serial No. 386,284.

To all whom it may concern:

Be it known that I, EDWARD ERICKSON, a citizen of the United States, residing at Beverly, in the county of Essex and State 5 of Massachusetts, have invented certain new and useful Improvements in Machines for Operating on Shoe Bottoms; and I do hereby declare the following to be a full, clear, and exact description of the invention, 10 such as will enable others skilled in the art to which it appertains to make and use the same.

This invention relates to machines for operating on shoe bottoms and more particularly to work-supports for use in such machines.

Although not limited thereto, the present invention is especially adapted for use in connection with welt butting and tacking 20 machines. In welt butting and tacking machines a welted, unsoled shoe is held in position for the butting operation by a pair of welt supports which project into the welt crease beneath the ends of the welt. After 25 being butted, the ends of the welt are tacked to the insole. The welt supports do not always hold the shoe with sufficient firmness to receive the impact of the blows delivered by the tacker mechanism and as a result the 30 welt ends are often improperly tacked to the insole. The shoe may be rigidly supported by means of a jack or spindle, but the use of such supporting means requires additional manipulation of the shoe by the operator in placing it upon the jack and removing it therefrom.

One object of the present invention is to provide means for firmly supporting a lasted, unsoled shoe in position to be operated 40 upon by devices such as the butting and tacking instrumentalities of a welt butting and tacking machine, without the use of a jack or similar work-supporting device.

With this object in view, one feature of 45 the invention contemplates the provision in a machine for operating upon shoe bottoms having a device for delivering a blow against the shoe, of a work-support for securely holding the shoe in position to be operated 50 upon and firmly sustaining it against the impact of the blow, by engagement with the counter portion of the upper above the comb of the last.

It is desirable that the work-support shall 55 not interfere with the free manipulation of

the shoe as it is being presented by the operator to the welt supports, or with the ready removal of the shoe at the completion of the bottoming operation. To this end, another feature of the invention contemplates the provision in a machine for operating on shoe bottoms having means for positioning the shoe for the bottoming operation, of a normally retracted work-support moved by the machine into supporting engagement with the shoe, after the shoe has been positioned, and then retracted from the shoe at the completion of operations thereon.

A still further feature of the invention 70 consists in certain features of construction and arrangement of the work-support and its actuating mechanism, whereby the support is adapted to automatically adjust itself to the particular shoe which is to be 75 operated upon so as to support the shoe in the exact position determined by the positioning means, irrespective of the style or size of the shoe, and which will operate 80 equally well on both right and left shoes.

The invention further consists in the features of construction and combinations of parts hereinafter described and particularly pointed out in the appended claims, the 85 advantages of which will be apparent to those skilled in the art.

The various features of the invention will be best understood from a description of the preferred embodiment thereof, illustrated in the accompanying drawings, in which the 90 invention has been shown as embodied in a welt butting and tacking machine such as that disclosed in United States Letters Patent No. 1,373,553, granted Apr. 5, 1921, 95 on my application.

In the drawings, Figure 1 is a view in side elevation showing so much of the machine of said prior patent as is necessary to illustrate the embodiment therein of the present invention; Fig. 2 is a plan view, 100 on an enlarged scale, showing the work-support detached from the machine, together with a portion of the actuating mechanism therefor; Fig. 3 is a view, in front elevation, of the parts shown in Fig. 1; Fig. 4 105 is a detail sectional view, on an enlarged scale, taken on the line 4—4 of Fig. 3; Fig. 5 is a detail sectional view, also on an enlarged scale, taken on the line 5—5 of Fig. 2; and Figs. 6 and 7 are detail views illus- 110

trating, in plan and side elevation, respectively, a portion of the actuating mechanism for the work-support.

In the embodiment of the invention illustrated in the drawings, the portions of the welt butting and tacking machine which are illustrated, are the back-gage 8 (Fig. 3); the welt supports 10; the welt butting knives 12 (see also Fig. 1), their carriers 14, and the knife-operating slides 16; the swinging side-frames 18, upon which the welt supports and the knife-operating slides are mounted; the nozzles 20 of the tacker mechanism; the main driving shaft 22; and the crank-pin 24, carried by the main shaft, which actuates the tack delivering mechanism; all of which are carried by the head 26 which is mounted on the supporting column 28. The above named parts, together with the actuating mechanisms therefor, and all other parts not hereinafter specifically referred to, are constructed and arranged to operate in substantially the same manner as that of the corresponding parts of the machine of the above-named patent. For a full and complete description of the construction and operation of said parts reference may be had to said patent.

To firmly support the shoe for the performance of the welt butting operation and to sustain it against the blows of the tacker mechanism, a work-support is provided, comprising a pair of oppositely disposed clamping arms 30, which are carried by a bracket 32, at the front of the head 26. The bracket 32 consists of a two-armed forward extension of a flat plate 34, which is interposed horizontally between the head 26 and the supporting column 28 of the welt butting machine, and is rigidly held in place by the bolts that secure together the head and the column. The clamping arms 30 are mounted for horizontal swinging movement on pivot studs 36 rising from the arms of the bracket 32. At its forward extremity, each clamping arm 30 carries a shoe-supporting pad 38, the pads 38 being adapted to engage the counter portion of the upper, above the comb of the last, on opposite sides of the shoe. The pads 38 are constructed of suitable soft or yielding material to prevent injury to the shoe and, as shown in Figs. 2, 3 and 5, they are carried by a holder or plate 40. Each pad holder 40 is formed at one side of a cylindrical stem 42 (Fig. 5) extending downwardly from the pad into a vertical socket 44 in the clamping arm 30. The stems 42 are confined in the sockets 44 by means of retaining screws 46, which are threaded into the stems and project through transverse slots 48 in the walls of the sockets, the slots 48 permitting the stems 42 to turn a limited amount in their sockets, and thus enabling the pads 38 to adjust themselves to the longitudinal angularity of

the opposite sides of the counter portion of the upper. The shoe-engaging faces of the pads 38 are disposed at a slight angle to their stems 42, in order that they may conform to the vertical pitch of the opposite sides of the shoe. In order to re-enforce the clamping arms 30 against the downward thrust imparted thereto by the blows of the tacker mechanism, the arms of the bracket 32 are extended forwardly, beyond the pivot studs 36, and terminate in flat segmental bearing faces 50 which engage similar bearing faces on the under side of the clamping arms, at the forward ends of the latter. With such a construction, a wide bearing surface is provided for the clamping arms, however they may be radially positioned while supporting the shoe.

In order that the supporting pads 38 may be automatically moved into supporting engagement with the shoe, after the shoe has been positioned by the welt supports and before the welt butting operation begins, and retracted from the shoe to facilitate removal of the latter at the completion of the welt butting and tacking operations, the supporting pads are normally maintained in retracted or inoperative positions, and mechanism is provided for actuating the clamping arms 30 to swing the pads against the sides of the shoe, and to retract them therefrom, at the proper time. To this end each clamping arm 30 is provided with a rearward extension 54 (Fig. 2), the arm 30 and the extension 54 constituting a lever 100 which is fulcrumed upon the pivot stud 36. The extensions 54 of the clamping arms curve inwardly toward each other and are connected by a coiled spring 56 which tends to swing the forward ends of the clamping arms apart and to hold the free extremities of the clamping arm extensions 54 in engagement with a pair of inclined faces 58 that are formed on opposite sides of a wedge-block 60, by means of which the 110 clamping arms are actuated. The wedge-block 60 is carried at the upper end of an arm 62 which is secured to a rock-shaft 64 that is journaled in a bearing in the bracket 32.

In order that the shoe supporting pads 38 may be positioned to properly support right and left shoes, or shoes of different styles and sizes, provision is made for permitting swinging movement of either of the clamping arms 30, independently of the other of said arms. To this end the wedge-block 60 has a sliding or floating connection with its supporting arm 62, which insures that the extensions 54 of both clamping arms will be engaged by the wedge-block before any pressure tending to clamp the shoe is applied to either of said arms. This floating connection is attained by means of a lug 68 of the shape shown in Fig. 7, the 130

lug depending from the under side of the wedge-block, which is dovetailed for sliding movement in a correspondingly shaped groove 70 in the top edge of the supporting arm 62. The upper edge of the arm 62 is flattened to engage a flat bearing face on the under side of the wedge-block and thus support the wedge-block against tilting relatively to its supporting arm.

10 The rock-shaft 64 is rotated to actuate the wedge-block 60 and cause the supporting pads 38 to clamp the shoe, by means including an arm 74 which is secured to the rock-shaft 64 and extends substantially at right angles to the arm 62 so that the arms 74 and 62 constitute in effect a bell-crank lever. The rear extremity of the arm 74 is operatively connected with the crank-pin 24, on the main drive shaft 22, by means whereby 15 said arm is swung yieldingly in a direction to effect the clamping of the shoe, and positively in the opposite direction. To this end the rear of the arm 74 is pivotally connected, as shown in Figs. 1, 3 and 4, with a 20 sleeve 76 that is adapted to slide upon a rod 78, the upper end of which is pivoted upon the crank-pin 24. The sleeve 76 is supported upon the rod 78 by bearing upon the hub of a hand-wheel 80 which is threaded 25 upon the lower end of the rod. A spring 82 surrounds the rod 78 and is interposed between the sleeve 76 and a shoulder 84 at the upper end of the rod.

In operation, the shoe is held with its 30 rear or heel portion against the back-gage 8, whereby the shoe is positioned longitudinally with the welt ends opposite the welt support as in the machine of the patent hereinbefore referred to. The operator then 35 depresses a foot treadle which is not shown in the drawings, but is illustrated and described in the prior patent. The depression of the treadle operates, in the usual manner, first to cause the welt supports to be projected into the welt crease, on opposite sides of the shoe, to position the shoe for the welt butting and tacking operation, and then to start the machine in operation, under power. As the main shaft 22 rotates in the direction 40 of the arrow in Fig. 1, the crank-pin 24 moves downwardly, and through the medium of the spring 82, the arms 74 and 62 are yieldingly swung in a direction to force the inclined faces 58 of the wedge-block 60 across the opposed rear extremities of the clamping arm extensions 54, thus spreading said extensions apart and swinging the clamping arms 30 toward each other to clamp the shoe. The construction of the 45 wedge-block actuating mechanism is such that the shoe-supporting pads 38 will be brought into engagement with the shoe before the crank-pin 24 reaches the lowermost portion of its path of movement. During 50 the remaining portion of the downward

movement of the crank-pin, the spring 82 will be compressed between the shoulder 84 and the sleeve 76, and the hand-wheel 80 will be moved downwardly away from the sleeve. The force of the compressed spring 70 82 will then act on the arms 74 and 62 and wedge-block 60, to securely clamp the shoe between the shoe supporting pads 38. While the crank-pin 24 is moving through the lowermost portion of its path of rotation, and the shoe is held securely supported, the welt butting and tacking operations occur. During the latter half of the cycle of operations of the machine, as the crank-pin 24 moves upwardly, the compression of 75 the spring 82 is relieved, and when the hub of the hand-wheel 80 engages the sleeve 76, the arms 74 and 62 and wedge-block 60 will be positively returned to their normal inoperative positions. The force with which the 80 shoe is to be clamped may be varied by turning the hand-wheel 80 thereby varying the normal compression of the spring 82. In order that the hand-wheel 80 may be 85 positively secured in adjusted position on the rod 78, the hub of the wheel is split and is provided with a clamping screw 86 for contracting the hub and locking the hand-wheel against turning on the rod.

When a shoe is positioned for the welt 90 butting operation the counter portions usually extend unequally on opposite sides of a vertical plane located midway between open clamping arms 30. Accordingly, as the shoe supporting pads 38 move inwardly 100 to clamp the shoe, it usually happens that one pad will engage the shoe before the other. By means of the sliding or floating connection between the wedge-block 60 and the arm 62, the wedge-block is permitted to 105 slide laterally with respect to said arm after one of the pads 38 has engaged the shoe, thereby causing the other pad to be brought into supporting engagement with the shoe before pressure is applied to either of the 110 clamping arms 30. In this way there is no tendency for the action of the clamping arms to tip or displace the shoe laterally out of the position in which it was first located by the welt supports.

115 By means of the herein described work support the shoe is clamped in the position determined by the welt supports and is firmly held in said position during the welt butting and tacking operations. The work 120 support sustains the shoe against the blows of the tacker mechanism so that the shoe will not be displaced thereby and thus the proper tacking of the welt ends to the insole is insured. The work-support, being normally retracted and automatically moved into and out of engagement with the shoe, will not interfere with the presentation of the shoe to the machine by the operator, or 125 the removal of the shoe from the machine 130

after it has been operated upon, and consequently will not retard the operative speed of the machine.

While it is preferred to employ the specific construction and arrangement of parts herein shown and described, it will be understood that this construction and arrangement is not essential except so far as specified in the claims and may be changed or modified without departing from the spirit and true scope of the invention.

What is claimed as new is:—

1. A machine for operating on the bottom of a lasted unsoled shoe having, in combination, means for operating on the shoe bottom, and means for supporting the shoe in position to be operated upon comprising devices for engaging in the welt crease and against the counter portion of the upper 20 above the comb of the last.
2. A machine for operating on the bottom of a lasted unsoled shoe having, in combination, means for operating on the shoe bottom, means for positioning the shoe laterally 25 for the bottoming operation, and a work support adapted to be brought into engagement with the opposite sides of the counter portion of the upper after the shoe has been positioned for said operation and acting to 30 support the shoe without disturbing its lateral position.

3. A machine for operating on the bottom of a lasted unsoled shoe having, in combination, tacker mechanism, means for engaging 35 in the welt crease to position the shoe for the operations to be performed thereon, devices for engaging the counter portions of the upper on opposite sides of the shoe to support the shoe while being operated upon, 40 and means for operating the tacker mechanism to drive tacks into the shoe bottom while the shoe is thus supported.

4. A machine for operating on the bottom of a lasted unsoled shoe having, in combination, means for delivering a blow against 45 the shoe bottom, and means for supporting the shoe against the impact of the blow comprising a device arranged to close against the counter portion of the upper between 50 the bulge of the last and comb of the last.

5. A machine for operating on the bottom of a lasted unsoled shoe having in combination, means for delivering a blow against the shoe bottom, means for positioning the shoe for the bottoming operation, and means 55 for securely clamping the shoe as positioned and sustaining it against the impact of the blow comprising devices for engaging the counter portion of the upper above the 60 comb of the last on opposite sides of the shoe.

6. In a machine for operating on lasted shoe bottoms provided with a tool for delivering a blow against the shoe, means for 65 positioning the shoe relatively to said tool,

and means automatically brought into engagement with the sides of the last beneath the bulge of the last for supporting it to receive the impact of said blow.

7. In a machine for operating on lasted 70 shoe bottoms, means for positioning the shoe bottom up for the bottoming operation, a normally retracted device for supporting the shoe and last while being operated upon, and means for automatically projecting said device into supporting engagement with a narrow portion of the shoe and last below the widest part of the last and for retracting it therefrom.

8. In a machine for operating on shoe bottoms, means for positioning the shoe for the bottoming operation, and means for supporting the shoe while it is being operated upon comprising normally retracted independently movable supports adapted to engage 85 the counter portion of the upper on opposite sides of the shoe, and means for bringing said supports into clamping engagement with the shoe and retracting them therefrom.

9. In a machine for operating on lasted shoe bottoms, a normally retracted device for supporting the shoe while being operated upon, means for yieldingly projecting said device into supporting engagement with the 95 shoe beneath overhanging portions of the last and for positively retracting it therefrom.

10. A shoe supporting device comprising 100 a pair of pivoted clamping arms for engaging the counter portions of the upper on opposite sides of a shoe firmly to support the shoe for an operation to be performed thereon, and means for actuating the clamping arms to engage and release the shoe, said means being constructed and arranged to permit independent movement of either of said clamping arms relatively to the other to cause said arms automatically to adjust themselves to shoes positioned with their counter portions unequally distant from a plane located midway between the pivots of the clamping arms.

11. A shoe supporting device comprising 115 a pair of levers having oppositely disposed ends for clamping a shoe, a wedge arranged to move transversely of the shoe and to engage the other ends of said levers, means for actuating the wedge to swing the levers in a direction to clamp the shoe, and means for swinging the levers in the opposite direction to release the shoe.

12. A shoe supporting device comprising 120 a pair of pivoted clamping arms adapted to swing toward and from each other to bring their free extremities into and out of clamping engagement with the opposite sides of a shoe, means for actuating the clamping arms firmly to clamp the shoe in 125 position to be operated upon, and bearings 130

engaging the clamping arms adjacent their free extremities to support them in all positions within their range of swinging movement.

5 13. A shoe supporting device comprising a pair of levers having oppositely disposed ends for clamping the shoe, means for separating the other ends of the levers to cause said first-mentioned ends to clamp the
10 shoe, and means permitting lateral drift of said separating means relatively to the shoe so that the levers will close equally upon the shoe irrespectively of the lateral position of the shoe and the shoe will be clamped in
15 that position upon further operation of said separating means.

14. A device for supporting an inverted shoe and last, comprising clamping means for engaging opposite sides of the shoe below
20 the bulge of the last, means for determining the lateral position of the shoe, and means for operating the clamping means to cause both sides of the last to be engaged by the clamping means irrespectively of the
25 lateral position of the shoe and then to cause clamping pressure to be applied equally to the two sides of the shoe and last.

15. A shoe supporting device comprising
30 means for locating an inverted shoe and last laterally, a pair of levers independently pivoted between their ends, one end of each lever having a clamping pad arranged to engage the side of the shoe, and means for actuating the opposite end of one of the
35 levers until its end engages the shoe, then actuating the other lever until its pad engages the shoe and then actuating both levers together to clamp the shoe in the position determined by said locating means.

40 16. A machine of the class described hav-

ing, in combination, means for operating upon the bottom of a lasted shoe, means for determining the lateral position of the shoe relatively to the operating means, and clamping means arranged for movement to
45 engage the sides of the shoe and last below the operating means, said means being constructed and operated to apply equal pressure to the shoe and last irrespectively of their lateral position.
50

17. A machine of the class described having, in combination, means for operating on an inverted shoe on its last, means engaging opposite sides of the last adjacent to the cone of the last, and means for applying
55 equalized pressure to sustain the last irrespectively of the lateral position of the two sides relatively to the operating means.

18. In a machine of the class described, shoe clamping means comprising members
60 arranged to engage the sides of the shoe below the shoe bottom at points where the last is narrower than its greatest width, a wedge arranged for movement longitudinally of the shoe and connections between
65 the wedge and the clamping members to cause them to clamp the shoe upon movement of the wedge.

19. In a machine of the class described, shoe clamping means comprising members
70 arranged to engage the sides of the shoe between the shoe bottom and the comb of the last, a wedge arranged for movement longitudinally and laterally, and connections between the wedge and the clamping means to
75 cause equal pressure to be applied by the clamping means to the shoe upon longitudinal actuation of the wedge.

EDWARD ERICKSON.
